UNITED STATES PATENT OFFICE.

DANIEL L. IRVIN, OF CURWENSVILLE, PENNSYLVANIA, ASSIGNOR TO A. H. IRVIN COMPANY, INC., OF CURWENSVILLE, PENNSYLVANIA, A CORPORATION.

STAPLE BINDER.

Application filed December 13, 1921. Serial No. 522,084

To all whom it may concern:

Be it known that I, DANIEL L. IRVIN, a citizen of the United States, residing at Curwensville, in the county of Clearfield and State of Pennsylvania, have invented certain new and useful Improvements in Staple Binders, of which the following is a specification.

My invention relates to improvements in staple binders, of the form shown in the application filed by myself under date of October 20, 1921, Serial No. 509,067, and the object of my improvement is to incorporate in a staple binder of the general form mentioned means for guiding the individual staple that is driven by the plunger whereby said individual staple will cooperate with the plunger and anvil for effecting the binding of materials that are operated upon so as to improve the efficiency of the staple binder.

In the accompanying drawing:—

Figure 1 is a side elevation of my improved staple binder.

Figure 2 is a plan view of the same.

Figure 3 is a front elevation of the same.

Figure 4 is a side elevation on an enlarged scale and in part broken away.

Figure 5 is a view corresponding to Fig. 4 with the parts in a different position.

Figure 6 is a plan view of the sliding sleeve and a portion of a staple strip shown in broken lines.

Figure 7 is a sectional view on the line 7—7 of Fig. 6.

Figure 8 is a perspective view of the sliding sleeve.

Figure 9 is a fragmentary view of the interior of one of the side plates.

Figure 10 is a sectional view on the line 10—10 of Fig. 9.

Figure 11 is a perspective view on a still further enlarged scale of part of one of the staple strips.

Figure 12 is a plan view of the blank for the sliding sleeve.

The staple binder to which my invention is applied may correspond in its general form to that shown and described in the application mentioned or to any other form that operates on a staple strip of the form shown in Fig. 11 for severing the individual

staples from said strip and driving and clenching the same, so that a brief description of the general structure will suffice.

Such general structure may comprise a base 10 having at the front end the anvil 11 for clenching the staples 12 in cooperation with the plunger 13 after they have been severed from the staple strip and are forced downwardly by the continued movement of the plunger, said staple strip being composed of a series of individual staples 12.

At the rear end of the base 10 is a pair of upstanding ears 14, positioned in spaced relation, that support the pivotal pin 15.

The base 10 serves as the fixed member, and a moving member, designated generally by the character 16, is operatively connected thereto by the pivotal pin 15.

A pair of ways 17 at the front part of the moving member 16, positioned in spaced relation, engage with the side edge portions of the plunger 13 and serve to guide the plunger in its upward and downward movement.

The filler piece 18 that extends along the bottom of the moving member 16, opposed to the base 10, is positioned between the two side plates 19 of the frame or casing; has its upper portion 20 reduced in width so as to serve as the guide for the staple strip; supports by its front end the die 21; supports by the lower portion 22 suitable dowel pins 23 for positioning the side plates 19; and has the rear end portion extended between the ears 14 and pivotally supported by the pin 15.

The said lower portion 22 also has holes for the two holding screws for holding the side plates 19 in place, comprising the screw 24 at the rear and the screw 25 at the front.

The front screw 25 serves also as the means for holding the die 21 in place, said die 21 being in the form of a removable piece.

The upper part of the casing for the moving member 16 is formed by the side plates 19 which have their body portions positioned in spaced relation to provide a housing for the staple moving or feeding mechanism that cooperates with the plunger 13. The form of the said upper part of the casing is generally triangular, with a sloping or inclined rear and upper wall 26, and the closure for

the said rear and upper portion is provided by means of inwardly turned, opposed flanges 27 on the said plates 19.

At the upper, front part of the casing, being at the upper end of the ways 17, is a seat 28 for the spring 29 that cooperates with the knob 30 at the upper end of the plunger 13 so as to tend to hold said plunger in the uppermost position.

10 The staple strip feeding mechanism is similar to that shown and described in the specification referred to above, being actuated by a lug 31 on the plunger 13, and comprises a feeding pawl 32 and a holding pawl 33.

15 The feeding pawl 32 is supported by a pivotally supported dog 34, the latter having a lug 35 that cooperates with the nose 31 on the plunger 13, and a spring 36 serves to 20 position the said feeding pawl 32 relatively to the dog 34.

A spring 37 serves to position the holding pawl 33.

25 The individual staples 12 are of U-shape, as is usual, and they are connected together by means of connecting necks 38 that serve to inter-connect the yoke portions 39 of the adjacent individual staples 12, whereby there is provided a backbone structure 40 30 that extends continuously from end to end of the staple strip, said strip as a whole being designated by the character 41.

35 The yoke portions 39 extend transversely across the backbone 40 and in use the combined structure formed by said yoke portions 39 and the necks 38, and constituting the backbone 40, as described, rests upon the upper face of the reduced, upper portion 20 of the filler piece 18.

40 The legs 42 of the individual staples 12 hang downwardly from the ends of the yoke portions 39 and travel in the spaces 43 at the sides of the reduced, upper portion 20, which spaces 43 are closed on the outer 45 sides by the side plates 19.

45 Thus said reduced upper portion 20 of the filler piece 18 serves as the guide or support for the staple strip 41 and is the part that has the cutting edge at the front end for 50 cooperating with the cutting edge on the plunger 13. The cutting edge 44 on the support or upper portion 20 may be integral with the filler piece 18 or may be provided on a removable and adjustable die 21, as 55 shown.

55 The cutting edge 45 on the plunger 13 operates to sever the neck 38 as the plunger is lowered and the continued movement of the plunger 13 serves to drive the severed 60 staple 12 along the channel 46 between the filler piece 18 and the opposed front wall portions 47 of the ways 17. Previous to being severed the end staple 12 is held overhanging the filler piece 18, at the upper portion of the channel 46, and with the legs 65

42 held against the front wall portions 47, the projecting end portion of the neck 38 that was left by the previous cut being housed within the space 48 between the opposed edges of said front wall portions 47 70 of the ways 17.

The means for guiding the staple will now be considered.

Said means comprise a sliding sleeve structure 50 that fits around the plunger 13 and 75 is mounted thereon for sliding movement and is itself adapted to slide in the ways 17, said sleeve structure 50 serving virtually as a lining for the said ways 17. The lower end portion 52 of said sleeve structure 50 extends 80 around the staple 12.

A spring 51 is interposed between the sleeve structure 50 and the plunger 13, at the front portion, as shown, and serves to produce a frictional holding effect whereby 85 the parts will be held in a particular relative position until disturbed in a positive manner and relative longitudinal, sliding movement is effected.

The plunger 13 carries with itself the 90 sleeve structure 50 generally in its upward and downward movements and near the end of such movement of the plunger the corresponding movement of the sleeve structure 50 is checked.

95 Such checking is effected in the structure shown by having the ends of the sleeve structure abut alternately against the anvil 11 at the lower end and against the bottom face of some part of the structure of the seat 28 100 for the plunger operating spring 29 at the upper end.

The plunger 13 has on the front face a pair of cross-notches 53 that register with a V-shaped rearwardly directed off-set 54 105 in the spring 51 in the extreme positions of the sleeve structure 50 on the plunger 13.

The spring 51 is of the same length as the sleeve structure 50 and abuts against the same contact faces as the sleeve structure so 110 that it is positively limited in its movement along the plunger in the same manner as said sleeve structure.

The lug or nose 31 on the plunger 13 is part of a fin 55 that extends longitudinally 115 along the rear face of the plunger, as in the other structures referred to.

The sleeve 50 has its rear wall portion of interrupted form, comprising two opposed and similar, inwardly directed wings or 120 flanges 56 that are separated by a space 57, which space 57 provides clearance for the fin 55 mentioned and also for other parts in certain positions, such as the die 21 and the neck 38 that connects adjacent staples 125 12 and which under operating conditions are in the same vertical plane as said fin 55.

130 It is important to note that under such operating conditions the wings 56 will register with the space 58, one on each side of the

neck 38 that connects the last staple 12 with the next to the last, being the space 58 between the adjacent legs 42 of the staples mentioned in each case. The functions of said wings 56 is to serve as a guide for the last individual staple 12 during the operations of severing the said staple from the staple strip and also during its downward movement after being so severed responsive to the downward movement of the plunger 13 in substantially the usual manner. Such guiding by the wings 56 is, however, confined to cooperation with the rear edge portions of the staple 12 that is being operated upon.

The cross-section of the sleeve structure 50 is such as to provide a pair of channels 58 on opposite sides that are the counterparts of the ways 17 and that themselves serve as ways for the side edge portions 59 of the plunger 13 during portions of the movement under operating conditions.

That is to say, the ways 17 serve as slide ways for the movement of the plunger 13 and the sleeve 50 combined during a part of the vertical movement in each direction of the plunger 13 and for the remainder of such movement the sleeve 50 serves as a lining for the ways 17 and the plunger travels with the channels 58 serving as guide-ways in cooperation with the side edges 59 of the plunger 13.

The staple 12 to be operated upon is directly under the part of the plunger 13 that is bounded by the side edges 59.

By projecting the sleeve 50 below the plunger 13 that lower portion 52 thereof is adapted to serve as a lining for the channel 46 so that the space bounded by the two channels 58 serves as the chute or passage for the staple 12 that is being driven, and the parts are constructed and arranged so that said sleeve 50 cooperates with the staple 12 in the manner mentioned.

The cross-section of the sleeve 50 is completed by means of a U-shaped connecting portion 60 that houses the forwardly extending body portion 61 of the plunger 13 and which has sufficient extent to house also the spring 51 which serves as the frictional holding member, as described.

The front wall 63 of the U-shaped connecting portion 60 is provided with an opening 64 of appreciable length through which the middle portion of the spring 51 is exposed.

The channels 58 are each bounded on the rear by one of the wings 56, on the front by a generally similar wing 65, and at the outside by the side wall 66 that interconnects the opposed wings 56 and 65.

Thus the front wings or walls 65 are adapted to cooperate with the front edge portions of the staple 12 in the same manner as the rear wings or walls 56 are adapt-

ed to cooperate with the rear edge portions thereof.

Also, the side, interconnecting walls 66 cooperate with the side faces of the legs 42 of the staple 12.

Thus the walls 56, 66, and 65 of the channels 58 serve in each case as positive guides for one of the legs 42 and the two channels cooperate as a guide for the staple as a whole. The individual channels each cooperate with three side faces or edges of the individual edge and the structure formed by the combination of the two channels 58 cooperates with the four sides or faces of the staple as a whole.

A part of the lower portion 52 of the sleeve 50 at the sides and rear is cut away, as indicated at 67 to provide clearance for the legs 42 and yoke 39 in feeding the staple strip forward after the end staple has been severed and driven, such feeding corresponding to the upward movement of the plunger 13. This construction permits of having excess length for the sleeve 50 for contacting with the base or anvil for limiting the downward movement of the sleeve before the plunger has completed its downward movement.

In operation, the important detail resides in the fact that with the plunger in its uppermost position the sleeve projects downwardly below the bottom face thereof. Thus as the plunger is forced downwardly it carries with it the sleeve and the lower portion 52 of the latter is adapted to engage with the staple before the plunger operates upon the staple strip.

Finally the sleeve loses its lead over the plunger and this is restored on the reverse movement.

During shifting movements of the sleeve and plunger relatively one to the other the V-shaped off-set 54 in the spring 51 moves along the space between the notches or recesses 53 on the plunger 13.

By cutting away the corner 67 of the lower portion 52 of the sleeve 50 as described the end staple is fed along so as to make contact with the front walls 65 of the channels 58, so that as the plunger descends and carries the sleeve with it the other walls of the channels 58 are adapted to complete the enclosure of the staple and serve as positive guide means therefor.

I claim as my invention:—

A staple binder having a supporting bar for supporting a staple strip, said bar having a cutting edge at one end, means for feeding said strip along said bar, a plunger having a cutting edge for cooperating with the cutting edge on the bar for cutting said staple strip, a guide structure enclosing said plunger, a sleeve interposed between said guide structure and plunger, a spring operative to provide a frictional holding effect

between said sleeve and plunger, a base opposed to said bar, means serving normally to position said plunger above said base and die, and means for positioning said sleeve normally so as to project downwardly below the bottom face of said plunger, the projecting portion of said sleeve comprising on

each side a three sided channel wall and a downward extension of one of the walls in line with the staple strip, and said sleeve being operative to slide along said plunger responsive to contacting with said base during downward movement of said plunger.

DANIEL L. IRVIN.
